LASTING MACHINE

Stanley Ernest Frampton, Leicester, England, assignor to United Shoe Machinery Corporation, Flemington, N. J., a corporation of New Jersey

Application July 15, 1948, Serial No. 38,810
In Great Britain September 15, 1947

30 Claims. (Cl. 12—8.7)

1

This invention relates to lasting machines, and more particularly to machines for lasting the toe ends of shoes. The invention is herein shown as applied to a power-operated toe-lasting machine of the same general character as disclosed in United States Letters Patent No. 2,134,148, granted on October 25, 1938, on an application of W. T. B. Roberts, but modified in certain respects as further disclosed in United States Letters Patent No. 2,138,308, granted on November 29, 1938, also on an application of W. T. B. Roberts. It is to be understood, however, that it is not thus limited in its applicability.

The machine to which the invention is thus shown as applied includes in its organization a pair of toe-embracing wipers which wipe the toe end of an upper heightwise of a last positioned bottom upward, i. e., perform what is commonly known as an upwiping operation on the upper, and thereafter wipe the margin of the upper inwardly over an insole on the last, such a machine being constructed especially for use on shoes of that type in which the margin of the upper throughout its width is lasted over the insole in generally parallel relation to the bottom of the last. The machine further includes a pair of upper-spreading fingers which are moved bodily lengthwise of the last from initial positions over the insole and are also swung widthwise of the last, each about an axis extending heightwise of the last, to spread the margin of the upper outwardly over the wipers prior to the upwiping operation. The fingers are thus carried to positions beyond the edge of the insole and are then moved downwardly toward the wipers. Thereafter they clamp the marginal portion of the upper outspread on the wipers and cooperate with them in tensioning the upper heightwise of the last during the upwiping operation. The fingers continue to control the margin of the upper until after the wipers have begun to wipe it inwardly over the insole, after which they are swung still farther outwardly and are moved farther bodily lengthwise of the last to positions beyond the wipers. They are then moved downwardly relatively to the wipers to positions where they will not interfere with the operation of tacking mechanism with which the machine is provided for fastening the toe end of the upper in lasted relation to the insole.

To adapt a machine constructed as above outlined for more effective use on men's shoes having comparatively heavy uppers, there have been provided heretofore, in combination with the

2

above-mentioned upper-spreading fingers which for purposes of designation may be termed main fingers, a pair of additional fingers arranged to rest on the insole and to spread the margin of the upper outwardly at the sides of the toe in locations beyond the main fingers, as disclosed in United States Letters Patent No. 2,379,543, granted on July 3, 1945, on an application of W. T. E. Roberts. In accordance with that disclosure the additional fingers are controlled independently of the main fingers and they continue to rest on the insole as the wipers approach them in the upwiping operation, so that they do not cooperate with the wipers in tensioning the upper until near the end of that operation. One of the objects of the present invention is to provide, for use on men's shoes, a more compact and unitary organization of upper-spreading and controlling means and one which will produce still better results in the lasting operation. To this end, the construction herein shown comprises a pair of upper-spreading fingers mounted for outward swinging movements and also for bodily movements lengthwise and heightwise of the last similarly to the above-mentioned main fingers used heretofore, and a pair of additional fingers arranged to act on the margin of the upper at the sides of the toe beyond the main fingers and operated and controlled, for the most part, by the same mechanism as the main fingers. That is, the mechanism for swinging the main fingers in outward directions and for moving them bodily lengthwise of the last also imparts outward movements widthwise of the last and bodily movements lengthwise of the last to the additional fingers. Each of the main fingers and the additional finger beyond it are connected together for relative swinging movement about an axis extending heightwise of the last in the course of the outward movements of the fingers, and mechanism is further provided for controlling each of the additional fingers with respect to movement about that axis to maintain the proper relation between it and the shoe as the fingers are moved outwardly. The additional fingers as well as the main fingers are moved outwardly beyond the edge of the insole and then downwardly toward the wipers, so that all the fingers cooperate with the wipers in tensioning the upper during the upwiping operation. The construction shown is also such that the additional fingers may be readily removed to permit fingers of a different size to be substituted or to permit the machine to be

used, if desired, without such additional fingers, as in operating on some women's shoes.

It will be evident that in order to move all the upper-spreading fingers arranged as above described far enough bodily lengthwise of the last to carry them beyond the wipers, so that they may be moved downward relatively to the wipers to provide room for the operation of the tacking mechanism, a substantially greater movement of the fingers is required than when only a single pair of fingers is used. For thus moving the fingers within space limitations imposed by portions of the structure of the machine novel mechanism is provided, comprising members one of which is moved by the other to impart a portion of the required movement to the fingers and is moved relatively to the other to increase the movement of the fingers.

For better results in operating on some kinds of uppers used in women's shoes, machines such as that to which the invention is herein shown as applied have sometimes been provided heretofore with auxiliary wipers arranged to rest on the upper faces of the main wipers and to have a supplemental wiping action on the upper at the sides of the toe in the upwiping operation, as disclosed in United States Letters Patent No. 2,234,279, granted on March 11, 1941, on an application of F. Ricks and J. W. Pratt. The present invention further provides for this purpose improved auxiliary wiping devices which may be used when the machine is to operate on such uppers. In the construction shown each of these auxiliary devices comprises a pair of small wiping plates positioned one beyond the other lengthwise of the edge of the shoe bottom and each mounted for free turning movement independently of the other about a separate axis extending heightwise of the shoe on a supporting member which is itself mounted for free turning movement about another such axis. The wiping plates, the wiping edges of which are somewhat curved lengthwise of the edge of the shoe bottom, are thus permitted to adjust themselves readily to the sides of the toe portions of shoes of different shapes. When such auxiliary wiping plates are used in combination with the previously mentioned upper-spreading fingers, the fingers actually clamp the margin of the upper outspread on these plates, which rest on the main wipers, and cooperate directly with the auxiliary plates in tensioning the upper heightwise of the last in the upwiping operation.

The novel features of the invention, including various novel details of construction and combinations of parts, will now be more particularly described with reference to the accompanying drawings and thereafter pointed out in the claims.

In the drawings,

Fig. 1 is a view in right-hand side elevation of a portion of the machine in which the invention is shown as embodied;

Fig. 2 is a view also in right-hand side elevation, on a larger scale, of a portion of the structure shown in Fig. 1, comprising one of the main upper-spreading fingers and parts associated therewith;

Fig. 3 is a plan view of the portion of the machine shown in Fig. 1;

Fig. 5 is a section on the line V—V of Fig. 3;

Fig. 6 is a section on the line VI—VI of Fig. 3;

Fig. 7 is a view in elevation in the direction of the arrow VII in Fig. 3, showing one of the addi-

tional upper-spreading fingers and parts associated therewith;

Fig. 8 is a view partly in plan and partly in section on the line VIII—VIII of Fig. 5;

Fig. 9 is a view of certain parts partly in plan and partly in section on the line IX—IX of Fig. 1;

Fig. 10 is a plan view of the auxiliary wiping devices in their initial positions, illustrating diagrammatically the corresponding positions of the main wipers and of the several upper-spreading fingers;

Fig. 11 is mainly a plan view with parts in section, showing the positions of the auxiliary wiping devices and the upper-spreading fingers when the fingers have been moved outwardly beyond the edge of the insole and downwardly toward the wipers;

Fig. 12 is mainly a plan view showing the relation of the main wipers to the shoe after wiping the margin of the upper inwardly over the insole and showing the auxiliary wiping plates and the upper-spreading fingers in their fully retracted positions;

Fig. 13 is a section on the line XIII—XIII of Fig. 10; and

Fig. 14 is a section on the line XIV—XIV of Fig. 10.

In a view of the disclosures in the previously mentioned Letters Patent, only as much of the machine is herein shown and will be described in detail as it is necessary to refer to for an understanding of the invention. The machine is provided with a pair of toe-embracing wipers 2 which operate on the toe end of a shoe positioned bottom upward in the machine and are moved upward from positions below the edge of the insole to perform an upwiping operation on the toe-end portion of the upper, after which they are advanced lengthwise of the shoe and are swung or closed inward laterally of the shoe to wipe the margin of the upper over the insole. For thereafter securing the upper in lasted position there is provided tacking mechanism (not shown) which is moved from an initial retracted position downwardly toward the wipers and inwardly over the shoe bottom into position to drive tacks through the margin of the upper and into the insole in locations beyond the inner edges of the wipers, as disclosed in Letters Patent No. 2,134,148.

The machine herein shown is further provided with a pair of auxiliary wiping devices 4 (Fig. 10) associated respectively with the wipers 2 but constructed differently from devices shown for a similar purpose in Letters Patent No. 2,234,279. Each of these devices comprises a pair of small wiper plates 6, each of approximately half-moon shape, which are supported on a carrier plate 8 mounted on a supporting member 10, this member having an outwardly extending bar-like portion 12 corresponding to the bar 21 shown in the last-mentioned Letters Patent. The supporting member 10 has an inwardly extending plate-like portion 14 (Fig. 13) arranged to underlie the carrier plate 8. The carrier plate extends into a slot in the member 10 and has an arcuate outer edge 16 in engagement with a correspondingly curved shoulder in the slot. The carrier plate is, moreover, pivotally mounted on a stud 18 in the plate-like portion 14 of the member 10 to swing freely about the stud, the axis of the stud being coincident with the axis of curvature of the edge 16. The wiper plates 6 of each of the auxiliary wiping devices are positioned one beyond the other

lengthwise of the edge of the shoe bottom for engagement with portions of the upper along the side of the toe extending from the vicinity of the tip line in directions both toward and away from the end of the toe. Each wiper plate has formed therein a groove 20 (Fig. 14) into which extends a tongue 22 on the carrier plate 8 to prevent relative movement heightwise of the shoe of the wiper plate and the carrier plate. Each wiper plate lies in a recess in the top of the carrier plate and has an arcuate outer edge 24 in engagement with a complementally curved shoulder on the carrier plate, and it is held in assembled relation to the carrier plate by a stud 26 which is mounted therein and extends through an arcuate slot 28 in the carrier plate. The wiper plates of each auxiliary wiping device are thus permitted to swing each independently of the other about a separate axis extending heightwise of the shoe relatively to the carrier plate 8 on which they are mounted, and the carrier plate itself is mounted for free swinging movement about another such axis. The wiper plates, therefore, readily adjust themselves to shoes of different shapes upon engagement therewith. As will be more fully understood by reference to Letters Patent No. 2,234,279, the auxiliary wiping devices are moved inward relatively to the wipers 2 along the top faces of the wipers, on which they are supported, and are pressed yieldingly inward against the upper at the sides of the toe through springs 30. In the upwiping operation they are moved upwardly by the wipers 2 and have a supplemental wiping action on the upper at the sides of the toe. Near the end of the upwiping operation they are projected short distances inwardly over the shoe bottom by the springs 30 and thus begin to wipe the upper inwardly at the sides of the toe ahead of the main wipers 2. Thereafter they are retracted from over the main wipers to positions in which they are well clear of the path of movement of the tacking mechanism, as illustrated in Fig. 12.

The machine is further provided with a pair of upper-spreading fingers 32 which spread the margin of the upper outwardly over the wipers and cooperate with them in tensioning the upper heightwise of the last during the upwiping operation, these fingers corresponding in purpose and function to the fingers 6 shown in Letters Patent No. 2,138,308. In the construction herein shown there is also provided an additional pair of upper-spreading fingers 34 arranged to act on the upper at the sides of the toe in locations beyond the fingers 32, which may be termed the main fingers, these additional fingers being used in place of the additional fingers 12 shown in Letters Patent No. 2,379,543. Both pairs of fingers 32 and 34 are supported by means hereinafter described on the front end portion of a rearwardly extending bar 36 (Figs. 1 and 3) provided at its rear end with an arcuate tongue 38 curved about an axis extending lengthwise of the shoe below the bar, the tongue extending into a correspondingly curved guideway formed in a slide 40 supported as hereinafter described for movements lengthwise of the shoe. A forwardly extending portion 42 (Fig. 1) of the slide 40 has an arcuate upper surface in supporting engagement with a correspondingly curved lower surface of the bar 36, these surfaces being curved about the same axis as the tongue 38. The bar 36 may therefore tip about an axis extending lengthwise of the shoe with the fingers 32 and 34 supported thereon to permit the fingers to adjust themselves in this manner to the portions of the margin of the upper which they engage

in the upwiping operation. Such tipping movement of the bar and the fingers is limited by a screw 44 threaded in the forwardly extending portion 42 of the slide 40 and extending into a transverse slot 46 formed in the bar, the screw and the slot preventing relative movement of the bar and the slide lengthwise of the shoe.

The fingers 32 are directly supported on small carrier blocks 48 which are generally triangular in plan, the fingers being provided with upwardly extending ribs 50 (Fig. 2) having thereon cylindrically formed surfaces curved about axes extending widthwise of the shoe and engaged by complementally curved surfaces formed in recesses in the blocks 48. The fingers, therefore, may tip about these axes to permit them to adjust themselves in this manner to the portions of the upper which they engage. The blocks 48 are pivotally mounted on hollow studs 52 (Fig. 4) extending upwardly through bores in the blocks near the inner rear corners of the blocks into bores in the front end portion of the bar 36 in which they are secured by setscrews 54 (Fig. 3). Slidingly mounted in the hollow studs 52 are two rods 56 extending upwardly from a central upper-spreading member 58 arranged to act on the margin of the upper at the extreme end of the toe in a location between the rear ends of the fingers 32. Springs 60 mounted between the upper ends of the rods 56 and shoulders on the bar 36 tend to move the rods and the member 58 in a downward direction, such movement being limited by screws 62 extending through bores in the bar 36 and threaded in the upper ends of the rods 56, the heads of the screws engaging shoulders on the bar. Sufficient space is afforded between the member 58 and the lower ends of the hollow studs 52 to permit relative movement of this member and the bar 36 against the resistance of the springs 60 and thus to permit the member 58 to adjust itself independently of the fingers 32 and 34 to the thickness of the portion of the upper which it engages.

For swinging the fingers 32 outwardly widthwise of the shoe about the axes of the studs 52 the outer corners of the triangular blocks 48 are connected by ball-and-socket joints 64 (Figs. 2 and 3) to the outwardly and forwardly curved front ends of rearwardly extending links 66. At their rear ends these links are connected by vertical studs 68 to a small inner slide 70 mounted for movements in directions lengthwise of the shoe along guideways provided by ribs 72 (Figs. 5 and 6) extending downwardly from the previously mentioned slide 40. A recess 74 is formed in the slide 40 to receive the rear end portions of the links 66. The means for operating the slide 70 to impart the outward swinging movements to the fingers 32 will be hereinafter described.

The third corner of each of the triangular blocks 48, located at the inner front end of the block, has an upwardly and downwardly extending bore therein for the reception of a stud 76 (Figs. 2 and 3) mounted in a bar 78 which is supported on the top of the block and serves as a support for the corresponding additional upper-spreading finger 34. Each bar 78 extends forwardly and rearwardly in the machine and has a bifurcated front end extending forwardly and somewhat outwardly from the locality of the stud 76 to provide an upwardly and downwardly extending slot 80 (Fig. 3) therein. A portion of the front end of each bar also extends downwardly and rearwardly to provide a lug 82

located below the block 48 and in contact therewith to receive the lower end of the stud 76. The slot 80 in the front end of each bar has therein a tongue 84 projecting rearwardly from a small block 86, and a pivot pin 88 extends through alined bores in the bifurcated front end of the bar and the tongue 84. The two blocks 86 have, forwardly of and parallel to the pins 88, bores for the reception of pins 90 which extend also through upstanding lugs on the fingers 34, the lugs being located at the opposite sides of the blocks. The pins 90 are held in place by spring-pressed pins 92 mounted in the blocks 86 and extending into recesses in the pins 90, the latter pins being removable by a pull applied thereto to permit the substitution of one pair of fingers 34 for fingers of a different size. The fingers 34 may tip to a limited extent about the pins 90, such tipping movements thereof being limited by their engagement with portions of the blocks 86. The manner in which the blocks 86 are mounted on the pins 88, moreover, permits the fingers 34 to be forced upward relatively to the bars 78 by pressure of the margin of the upper thereon against the resistance of spring-controlled plungers 94 (Figs. 1 and 7) which are mounted in the bars and engage the rear ends of the tongues 84 above the pins 88.

The fingers 34 are positioned immediately beyond the fingers 32 lengthwise of the shoe and, as shown in Figs. 10 and 11, their rear end faces are curved about vertical axes and lie in complementally curved recesses in the front ends of the fingers 32 to provide for substantially continuous engagement of the fingers with the margin of the upper lengthwise of the edge of the shoe bottom, sufficient leeway being provided, however, for the fingers to tip relatively to one another in the manner above described. Similarly, the fingers 32 are practically continuous with the central upper-spreading member 58. Initially the fingers 34 are substantially in alinement with the fingers 32 lengthwise of the shoe, as illustrated in Fig. 10. After the fingers have been moved downwardly into engagement with the insole, by means hereinafter described, the blocks 48 are swung about the studs 52 through the links 66 to impart outward upper-spreading movements to the fingers 32 and 34 simultaneously with rearward bodily movements of all the fingers and the central upper-spreading member 58 lengthwise of the shoe. It will be evident that each of the fingers 32 and the corresponding finger 34 beyond it are connected together for relative swinging movement about an axis extending heightwise of the shoe, i. e., about the axis of the stud 76, and that in the course of the outward movements of the fingers 34 widthwise of the shoe they have also, by reason of the swinging of the blocks 48, bodily rearward movements corresponding to components of swinging movement of the fingers 32 in that direction, their supporting bars 78 likewise receiving such bodily rearward movements. For controlling the fingers 34 with respect to movements about the axes of the studs 76 and for thereby maintaining them in proper relation to the shoe in their outward movements, the rear ends of the bars 78 carry rolls 96 lying in cam tracks 98 formed in the previously mentioned slide 40 relatively to which the bars are moved rearwardly in response to the swinging of the blocks 48.

The slide 40, which is connected by the head of the screw 44 to the finger-supporting bar 36 as hereinbefore described, is supported on a carrier 100 having dovetail guideways for the pre-

viously mentioned ribs 72 formed on the slide. This carrier comprises two opposite side portions which are bolted together in spaced relation to each other, and it is supported for movements in forward and rearward directions in substantially the same manner as the member 12 shown in Letters Patent No. 2,138,308. That is, it is supported near its rear end by a pivot pin 102 on the upper end of a forwardly and rearwardly movable cam-operated lever 104 and is supported near its front end by a pin 105 on the upper ends of a pair of links 106 which may swing forwardly and rearwardly, the lever 104 and the links 106 corresponding respectively to the lever 16 and the links 30 shown in the last-mentioned Letters Patent. For moving the upper-spreading fingers downwardly and for pressing them yieldingly on the insole at the beginning of the operation of the machine the links 106 are moved in downward directions by mechanism not herein shown but fully disclosed in said Letters Patent, this mechanism being operated by a groove cam 108 on a cam shaft (not shown). The lever 104 is operated by a groove cam 110 on the cam shaft 25 to move the carrier 100 bodily in a rearward direction at the time when outward upper-spreading movements widthwise of the shoe are imparted through the links 66 to the several fingers, thus moving the fingers and the central upper-spreading member 58 bodily lengthwise of the shoe through the slide 40 which is at that time locked to the carrier and which is connected, as above described, to the bar 36 supporting the fingers.

The means for thus locking the slide 40 to the carrier 100 comprises a pair of rolls 112 (Figs. 3, 6 and 8) which lie in slots 114 extending through the depending ribs 72 on the slide 40 and are of greater diameter than the width of the ribs. Small hardened blocks 116 secured in recesses in the carrier 100 are provided with V-shaped notches 117 into which the rolls initially extend for locking the slide 40 to the carrier, the rolls being held in locking positions by engagement of the opposite sides of the inner slide 70 therewith. When the slide 70, moved rearward relatively to the slide 40 by means hereinafter described, arrives in its rearmost position relatively to the slide 40, V-shaped notches 118 (Fig. 8) in the slide 70 are opposite the slots 114 in the ribs 72 and receive portions of the rolls 112 forced into them by the walls of the V-shaped notches 117 in the blocks 116, so that the slide 40 is unlocked from the carrier 100 and is locked to the slide 70 to permit these two slides to be moved rearwardly as a unit relatively to the carrier 100 for a purpose hereinafter explained.

For moving the slide 70 rearward relatively to the slide 40 to impart upper-spreading movements widthwise of the shoe to the fingers 32 and 34, there is provided an auxiliary slide 120 located immediately in front of the slide 70 and T-shaped in plan (Fig. 8) with its stem portion extending rearwardly into a recess in the slide 70, the auxiliary slide being movable along the same guideways as the slide 70. Extending rearwardly from the auxiliary slide 120 through bores in the slide 70 are two rods 122 which project beyond the rear end of the latter slide. These rods serve as supports for compression springs 124 which abut at their front ends against shoulders formed in the bores in the slide 70 and at their rear ends against shoulders formed in bores in a plate 126 secured to the rear end portion of the carrier 100. The springs 124, therefore, are

compressed by the rearward movement of the slide 70. Formed on the lower face of the auxiliary slide 120 are rack teeth 128 (Fig. 1) engaged by a pinion 130 freely rotatable on the previously mentioned pin 105. This pinion is engaged by teeth on an arcuate gear sector 132 formed on an arm 134 which is mounted to swing about a pin 136, the pin being secured in an arm 138 fast on the carrier 100. The arm 134 corresponds to the lever 197 shown in Letters Patent No. 2,134,148, but has no arm extending from it corresponding to the arm 203 therein shown. Also mounted to swing about the pin 136 is a lever 140 provided at its rear end with a roll 142 arranged to be engaged by a cam 144 on the previously mentioned cam shaft. The lever 140 corresponds to the lever 205 shown in the last-mentioned Letters Patent and has a forwardly extending arm 146 connected to the arm 134 by an adjusting device comprising a threaded stem 148 and other parts like corresponding parts in the last-mentioned Letters Patent. By turning the stem 148 the lever 140 may be swung about the pin 136 to raise or lower the cam roll 142 and thus to determine variably the amount of outward upper-spreading movements which will be imparted to the fingers 32 and 34 by the action of the auxiliary slide 120 on the slide 70. This adjustment will be such that in their outward movement widthwise of the last, accompanied by the bodily movements lengthwise of the last imparted to them by the carrier 100, the fingers will be carried beyond the edge of the insole to permit them to be moved downward toward the wipers prior to the upwiping operation.

When the wipers wipe the margin of the upper inwardly over the insole after the upwiping operation, the upper-spreading fingers are first moved bodily a short distance lengthwise of the shoe with the wipers by reason of the shape of the cam 110 which operates the carrier 100, similarly to the disclosure of Letters Patent No. 2,138,308. The fingers are then moved farther outwardly and are also moved farther bodily in a rearward direction until they are clear of the wipers to permit them to be moved downward relatively to the wipers to positions where they are out of the way of the tacking mechanism. When the fingers are at the limits of their outward movements the relation between the fingers 32 and the fingers 34 is such as illustrated in Fig. 12, the fingers 32 being substantially in alignment with each other widthwise of the shoe and the fingers 34 extending generally in a forward direction from the ends of the fingers 32. It will be evident, therefore, that in order to clear the wipers all the fingers must be moved a substantial distance farther rearwardly than the single pair of fingers shown in Letters Patent No. 2,138,308. Space limitations in the machine are, however, such that the required additional rearward movement cannot be imparted to the fingers merely by increasing the range of movement of the carrier 100. To complete the outward movements of the fingers, therefore, and to move them rearwardly the required additional distance, the inner slide 70 is connected by a link 150 to an arm 152 mounted to swing about the previously mentioned pin 102 on the carrier 100. The arm 152 has formed thereon an arcuate gear sector 154 engaged by another arcuate gear sector 156 formed on a bifurcated arm 158 pivotally mounted on the pin 136 on the carrier 100. The arm 158 takes the place of the arm 203 shown in Letters Patent No. 2,134,148 and is pro-

vided with a cam roll 160 engaged by a cam 162 on the cam shaft. When the upper-spreading fingers are swung outwardly as hereinbefore described by the action of the cam 144 on the arm 140 the inner slide 70, operated by the auxiliary slide 120, acts through the link 150 and the arm 152 to swing the cam roll 160 away from the cam 162. As the cams continue to rotate, the cam 162 at the proper time again engages the roll 160 and acts on the arm 158 to move the inner slide 70 farther rearward independently of and relatively to the auxiliary slide 120. In this manner the opening apart of the fingers is completed after the upwiping operation. The slide 70 is thus moved into engagement with inturned abutments 164 formed on the rear end of the slide 40, at which time the V-shaped notches 118 in the slide 70 arrive in positions opposite the rolls 112. The slide 40 then starts to move with the slide 70 relatively to the carrier 100 by reason of engagement of the slide 70 with the abutments 164, the rolls being forced out of the notches 117 in the blocks 116 and into the notches 118 in the slide 70 to unlock the slide 40 from the carrier 100 and lock it to the slide 70. Such rearward movement of the slides 40 and 70 as a unit relatively to the carrier 100, combined with further rearward movement of the carrier on which the means for thus moving the slide 70 is supported, serves to retract the upper-spreading fingers into positions to clear the wipers, as illustrated in Fig. 12.

As the inner slide 70 is moved rearward relatively to the auxiliary slide 120 in the manner above described the springs 124 are further compressed. In the return of the parts to starting positions these springs move the two slides 40 and 70, which are locked together by the rolls 112, forwardly as a unit until movement of the slide 40 relatively to the carrier 100 is stopped by the engagement of lugs 166 thereon with shoulders at the front ends of recesses 168 in the carrier. At this point the slide 40 is unlocked by the rolls 112 from the slide 70, since the rolls are opposite the V-shaped notches 117 in the blocks 116, and is again locked to the carrier 100. The slide 70 is then moved farther forward by the springs relatively to the slide 40 until a depending abutment 170 thereon engages shoulders at the front ends of recesses 172 (Fig. 1) in the carrier 100, this movement of the slide 70 serving to impart return movement to the auxiliary slide 120. It will be understood that before such return movements are imparted to the several slides the carrier 100 will have been swung upwardly by the links 106 until the upper-spreading fingers are above the plane of the wipers.

The manner of operation of the machine, in so far as it is of interest with reference to the present invention, will now be briefly summarized. A shoe having been properly positioned and jacked in the usual manner in the machine and such adjustments having been made as to cause the wipers and the upper-spreading fingers to operate properly on a shoe of that size and style, the operator starts the cycle of operations. At the beginning of the cycle the upper-spreading fingers 32 and 34, together with the central upper-spreading member 58, are moved downwardly into engagement with the insole by downward swinging movement of the carrier 100 about the pin 102, this movement of the carrier being effected by the cam 108 acting through the links 106 and through a spring (not shown) corresponding to the spring 46 shown in Letters Pat-

11

ent No. 2,138,308. After the fingers engage the insole this spring is compressed to press them yieldingly on the insole. The relation of the fingers to one another when they first engage the insole is illustrated in Fig. 10. The fingers are then moved bodily in a rearward direction by the carrier 100 operated by the cam 110 and the lever 104, the carrier imparting such movement to the fingers through the slide 40 which is at that time locked to the carrier by the rolls 112 and which is connected to the bar 36 supporting the fingers. Simultaneously with their rearward bodily movements outward swinging or opening movements are imparted to the fingers by the swinging of the blocks 48 about the studs 52, such swinging of the blocks resulting from rearward movement of the slide 70 connected to the blocks by the links 66. This movement is imparted to the slide 70 against the resistance of the springs 124 by the auxiliary slide 120 which is operated by the cam 144 acting thereon through the lever 140, the arcuate gear sector 132 and the pinion 130. As the fingers are thus swung outwardly, relative movement takes place between the fingers 32 and the fingers 34 about the axes of the studs 76, and the fingers 34, by reason of the swinging of the blocks 48, receive additional bodily rearward movements corresponding to components of rearward swinging movement of the fingers 32. In this operation the fingers 34 are controlled with respect to movements about the axes of the studs 76 by the cam tracks 98 in the slide 40 along which the rolls 96 on the rear ends of the bars 78 are carried as the fingers receive their bodily rearward movements due to the swinging of the blocks 48. The outward upper-spreading movements of the fingers, and their bodily rearward movements with the central upper-spreading member 58 due to the rearward movement of the carrier 100, are such as to carry the fingers and the central member beyond the edge of the insole, whereupon the carrier is swung downward by expansion of the above-mentioned spring acting on the links 106 to carry the fingers toward the wipers 2 which are at that time positioned a substantial distance below the edge of the shoe bottom.

As the wipers 2 are thereafter moved upwardly to perform the upwiping operation, the auxiliary wiper plates 6, which have been moved inwardly and pressed yieldingly against the upper along the sides of the toe through the springs 30 and have adjusted themselves to the contour of the toe, are moved upwardly by the wipers 2 and assist in the upwiping operation. Shortly after the beginning of the upwiping operation the outspread margin of the upper is clamped between the main wipers 2 and the central upper-spreading member 58 at the end of the toe and between the upper-spreading fingers 32 and 34 and the auxiliary wiper plates 6 along the sides of the toe. The fingers are so positioned that the fingers 32 cooperate mainly with those auxiliary plates 6 which are near the end of the toe and the fingers 34 cooperate mainly with the auxiliary plates which are farther from the end of the toe. By reason of this clamping action the upper is tensioned heightwise of the last in the upwiping operation. Since the plates 6 are each independently movable about an axis extending heightwise of the last and are supported on the carrier plates 8 each of which is itself movable about another such axis, the plates readily accommodate themselves to the varying contour of the sides of the toe throughout the upwiping

12

operation regardless of the style or size of shoe being operated upon. As soon as the auxiliary wiper plates have been moved upwardly far enough to clear the edge of the insole they are moved a short distance inwardly in wiping engagement with the upper by expansion of the springs 30. Thereafter the main wipers arrive in positions to wipe the margin of the upper inwardly over the insole and are advanced and closed to perform this operation on the upper. As these wipers begin their inward movements over the insole the upper-spreading fingers are first moved a short distance bodily with them lengthwise of the shoe by the carrier 100 and are thereafter opened still farther apart and are moved bodily in a rearward direction to carry them away from over the wipers. Such further opening movements of the fingers are effected by moving the slide 70 rearward relatively to the auxiliary slide 120 against the resistance of the springs 124, this movement of the slide 70 being effected by the action of the cam 162 on the lever 158. In this operation the fingers 34 are moved farther bodily in a rearward direction by the swinging of the blocks 48 and their positions with respect to swinging movements about the axes of the studs 76 are still determined by the cam tracks 98. When the slide 70 in its rearward movement arrives in position to engage the inturned abutments 164 on the slide 40, the latter slide is unlocked from the carrier 100 and is locked instead to the slide 70 by the rolls 112. These two slides thereafter move rearwardly as a unit relatively to the carrier 100 while the carrier also is moving farther rearwardly, the combined movements of the slides and the carrier serving to retract all the upper-spreading fingers to positions where they are clear of the wipers, as illustrated in Fig. 12, and thus to permit the fingers to be moved downward relatively to the wipers by downward swinging movement of the carrier 100 to provide sufficient room for the operation of the tacking mechanism. The auxiliary wiper plates 6 also are retracted from over the wipers as illustrated in Fig. 12 to positions out of the way of the tacking mechanism. After the tacking operation the parts of the machine are returned to their starting positions, the several slides being returned in the manner already fully explained.

It will be evident that in operating, for example, on men's shoes having heavy uppers the machine may, if desired, be used without the auxiliary wiper plates 6 and parts associated therewith, which may be removed without affecting the operation of other parts. In that case, the upper-spreading fingers 32 and 34 will clamp the upper directly on the wipers 2. In operating on some kinds of women's shoes, on the other hand, it may be desired to use the upper-spreading fingers 32 alone, in which case the additional fingers 34 may be readily removed in the manner explained.

Having described the invention, what I claim as new and desire to secure by Letters Patent of the United States is:

1. In a lasting machine, the combination with wipers for wiping an upper around the toe end of a last into lasted position, of a pair of upper-spreading fingers supported for swinging movements widthwise of the last each about an axis extending heightwise of the last, means for thus swinging said fingers and for also moving them bodily lengthwise of the last from positions opposite the bottom of the last to spread the mar-

gin of the upper outwardly over the wipers near the end of the toe, and another pair of fingers connected to said first-named fingers to move with them widthwise and lengthwise of the last for spreading the margin of the upper outwardly at the sides of the toe in locations beyond the first-named fingers.

2. In a lasting machine, the combination with wipers for wiping an upper around the toe end of a last into lasted position, of a pair of fingers supported for swinging movements each about an axis extending heightwise of the last to spread the margin of the upper outwardly over the wipers near the end of the toe, another pair of fingers movable to spread the margin of the upper outwardly at the sides of the toe in locations beyond said first-named fingers, each of the first-named fingers and the corresponding other finger beyond it being connected together for relative swinging movement about an axis extending heightwise of the last, and means for effecting such relative swinging movements of the first-named fingers and the other fingers while imparting outward upper-spreading movements to all the fingers.

3. In a lasting machine, the combination with wipers for wiping an upper around the toe end of a last into lasted position, of a pair of fingers supported for swinging movements each about an axis extending heightwise of the last to spread the margin of the upper outwardly over the wipers near the end of the toe, another pair of fingers for spreading the margin of the upper outwardly at the sides of the toe in locations beyond said first-named fingers, each of the first-named fingers and the corresponding other finger beyond it being connected together for relative swinging movement in the upper-spreading operation about an axis extending heightwise of the last, means for imparting upper-spreading movements to all the fingers, and additional means for controlling such relative swinging movements of the first-named fingers and the other fingers.

4. In a lasting machine, the combination with wipers for wiping an upper around the toe end of a last into lasted position, of a pair of fingers supported for swinging movements each about an axis extending heightwise of the last to spread the margin of the upper outwardly over the wipers near the end of the toe, another pair of fingers for spreading the margin of the upper outwardly at the sides of the toe in locations beyond said first-named fingers, each of the first-named fingers and the corresponding other finger beyond it being connected together for relative swinging movement in the upper-spreading operation about an axis extending heightwise of the last, means for imparting upper-spreading movements to all the fingers, members connected respectively to said other fingers, and cam means arranged to act on said members in the upper-spreading operation to control such relative swinging movements of the first-named fingers and the other fingers.

5. In a lasting machine, the combination with wipers for wiping an upper around the toe end of a last into lasted position, of a pair of fingers supported for swinging movements each about an axis extending heightwise of the last with components of movement lengthwise of the last to spread the margin of the upper outwardly over the wipers near the end of the toe, another pair of fingers for spreading the margin of the upper outwardly at the sides of the toe in locations beyond said first-named fingers, supports for said

tions beyond said first-named fingers, connections between said first-named fingers and the other fingers for imparting outward upper-spreading movements to the other fingers and for imparting to them also bodily movements lengthwise of the last corresponding to the components of movement of the first-named fingers in that direction, said connections being arranged to permit relative swinging movement of each of the first-named fingers and the corresponding other finger beyond it about an axis extending heightwise of the last in the upper-spreading operation, and means for controlling such relative swinging movements of the first-named fingers and the other fingers.

6. In a lasting machine, the combination with wipers for wiping an upper around the toe end of a last into lasted position, of a pair of fingers supported for swinging movements each about an axis extending heightwise of the last with components of movement lengthwise of the last to spread the margin of the upper outwardly over the wipers near the end of the toe, another pair of fingers for spreading the margin of the upper outwardly at the sides of the toe in locations beyond said first-named fingers, connections between said first-named fingers and the other fingers for imparting upper-spreading movements to the other fingers and for imparting to them also bodily movements lengthwise of the last corresponding to the components of movement of the first-named fingers in that direction, said connections being arranged to permit relative swinging movement of each of the first-named fingers and the corresponding other finger beyond it about an axis extending heightwise of the last in the upper-spreading operation, members connected respectively to said other fingers and movable with them lengthwise of the last, and cam means along which said members are thus movable for controlling such relative swinging movements of the first-named fingers and the other fingers.

7. In a lasting machine, the combination with wipers for wiping an upper around the toe end of a last into lasted position, of a pair of fingers supported for swinging movements each about an axis extending heightwise of the last to spread the margin of the upper outwardly over the wipers near the end of the toe, mechanism mounted for movement lengthwise of the last thus to swing said fingers, other fingers arranged to be moved outwardly widthwise of the last by that movement of said mechanism to spread the margin of the upper over the wipers at the sides of the toe in locations beyond said first-named fingers, each of the first-named fingers and the corresponding other finger beyond it being connected together for relative swinging movement about an axis extending heightwise of the last in the upper-spreading operation, and means arranged to act on said other fingers to control such relative swinging movements of the first-named fingers and the other fingers.

8. In a lasting machine, the combination with wipers for wiping an upper around the toe end of a last into lasted position, of a pair of fingers for spreading the margin of the upper outwardly over the wipers near the end of the toe, supports for said fingers mounted for swinging movements each about an axis extending heightwise of the last thus to operate the fingers, other fingers for spreading the margin of the upper outwardly at the sides of the toe in locations beyond said first-named fingers, supports for said

15

other fingers pivotally connected to said first-named supports to be moved thereby widthwise of the last and to permit them to swing relatively to the first-named supports about axes extending heightwise of the last in the upper-spreading operation, and means for controlling said last-named supports with respect to movements about said axes during the operation of the fingers.

9. In a lasting machine, the combination with wipers for wiping an upper around the toe end of a last into lasted position, of a pair of fingers for spreading the margin of the upper outwardly over the wipers near the end of the toe, supports for said fingers mounted for swinging movements each about an axis extending heightwise of the last thus to operate the fingers, other fingers for spreading the margin of the upper outwardly at the sides of the toe in locations beyond said first-named fingers, supports for said other fingers pivotally connected to said first-named supports to be moved thereby widthwise and lengthwise of the last and to permit them to swing relatively to the first-named supports about axes extending heightwise of the last, and cam means along which said last-named supports are thus movable lengthwise of the last for controlling them with respect to swinging movements about said axes.

10. In a lasting machine, the combination with wipers for wiping an upper around the toe end of a last into lasted position, of a pair of fingers for spreading the margin of the upper outwardly over the wipers near the end of the toe, supports for said fingers mounted for swinging movements each about an axis extending heightwise of the last thus to operate the fingers, other fingers for spreading the margin of the upper outwardly at the sides of the toe in locations beyond said first-named fingers, supports for said other fingers pivotally mounted on said first-named supports to be moved thereby widthwise and lengthwise of the last and to permit them to swing relatively to the first-named supports about axes extending heightwise of the last, the supports for said other fingers comprising bars arranged to extend lengthwise of the last and having cam rolls thereon, and cams along which said rolls are movable by the movements of said last-named supports lengthwise of the last for controlling them with respect to movements about said axes.

11. In a lasting machine, the combination with wipers for wiping an upper around the toe end of a last heightwise of the last and for thereafter wiping the margin of the upper inwardly over an insole on the last, of a pair of fingers for spreading the margin of the upper outwardly over the wipers near the end of the toe, another pair of fingers for spreading the margin of the upper outwardly at the sides of the toe in locations beyond said first-named fingers, means for moving all said fingers outwardly in engagement with the insole to positions beyond the edge of the insole prior to the wiping of the upper heightwise of the last, and a carrier for carrying all the fingers heightwise of the last toward the wipers after they have thus been moved outwardly.

12. In a lasting machine, the combination with wipers for wiping an upper around the toe end of a last heightwise of the last and for thereafter wiping the margin of the upper inwardly over an insole on the last, of a pair of fingers supported for swinging movements each about an axis extending heightwise of the last to spread the margin of the upper outwardly over the wipers near

16

the end of the toe, means for thus swinging said fingers and for also moving them bodily lengthwise of the last in engagement with the insole to positions beyond the edge of the insole prior to the wiping of the upper heightwise of the last, another pair of fingers arranged to be moved widthwise of the last to positions beyond the edge of the insole with the first-named fingers to spread the margin of the upper outwardly over the wipers at the sides of the toe in locations beyond the first-named fingers, and means for carrying all said fingers heightwise of the last toward the wipers after they have thus been moved to positions beyond the edge of the insole.

13. In a lasting machine, the combination with wipers for wiping an upper around the toe end of a last heightwise of the last and for thereafter wiping the margin of the upper inwardly over an insole on the last, of a pair of fingers for spreading the margin of the upper outwardly over the wipers near the end of the toe, supports for said fingers mounted for swinging movements each about an axis extending heightwise of the last to move the fingers outwardly widthwise of the last, means for thus swinging said supports and for also moving them bodily lengthwise of the last to carry the fingers to positions beyond the edge of the insole prior to the wiping of the upper heightwise of the last, another pair of fingers for spreading the margin of the upper outwardly at the sides of the toe in locations beyond said first-named fingers, supports for said other fingers connected to said first-named supports to be moved thereby to carry said other fingers outwardly beyond the edge of the insole with the first-named fingers, and means for carrying all said fingers heightwise of the last toward the wipers after they have thus been moved to positions beyond the edge of the insole.

14. In a lasting machine, the combination with wipers for wiping an upper around the toe end of a last into lasted position, of a pair of fingers supported for swinging movements each about an axis extending heightwise of the last to spread the margin of the upper outwardly over the wipers near the end of the toe, another pair of fingers supported for movements to spread the margin of the upper outwardly at the sides of the toe in locations beyond said first-named fingers, and means for imparting upper-spreading movements to all the fingers from initial positions in which said other fingers are substantially in alignment with the first-named fingers lengthwise of the last and for thereafter further moving the fingers to retracted positions in which the first-named fingers are substantially in alignment with each other widthwise of the last and the other fingers extend therefrom in directions generally lengthwise of the last.

15. In a lasting machine, the combination with wipers for wiping an upper around the toe end of a last heightwise of the last and for thereafter wiping the margin of the upper inwardly over an insole on the last, of a pair of fingers supported for swinging movements each about an axis extending heightwise of the last to spread the margin of the upper outwardly over the wipers near the end of the toe, another pair of fingers supported for movements to spread the margin of the upper outwardly at the sides of the toe in locations beyond said first-named fingers, mechanism including a member movable lengthwise of the last for imparting such outward upper-spreading movements to all said fingers prior to the wiping of the upper height-

wise of the last, another member movable lengthwise of the last thus to operate said first-named member, and means for moving said first-named member farther lengthwise of the last independently of said other member to impart further outward movements to said fingers after the wiping of the upper heightwise of the last.

16. In a lasting machine, the combination with wipers for wiping an upper around the toe end of a last into lasted position, of a pair of fingers supported for swinging movements each about an axis extending heightwise of the last to spread the margin of the upper outwardly over the wipers near the end of the toe, another pair of fingers supported for movements to spread the margin of the upper outwardly at the sides of the toe in locations beyond said first-named fingers, mechanism including a member movable lengthwise of the last for imparting such outward upper-spreading movements to all said fingers, another member movable lengthwise of the last thus to operate said first-named member by engagement therewith, and means for moving said first-named member farther lengthwise of the last relatively to said other member in the course of the operation of the machine to impart further outward movements to said fingers.

17. In a lasting machine, the combination with wipers for wiping an upper around the toe end of a last into lasted position, of a pair of fingers supported for swinging movements each about an axis extending heightwise of the last to spread the margin of the upper outwardly over the wipers near the end of the toe, another pair of fingers supported for movements to spread the margin of the upper outwardly at the sides of the toe in locations beyond said first-named fingers, mechanism including a slide movable lengthwise of the last for imparting such outward upper-spreading movements to all said fingers, another slide movable lengthwise of the last thus to operate said first-named slide by engagement therewith, cam-operated means for thus operating said other slide, and additional cam-operated means for moving the first-named slide farther lengthwise of the last independently of said other slide in the course of the operation of the machine to impart further outward movements to said fingers.

18. In a lasting machine, the combination with wipers for wiping an upper around the toe end of a last into lasted position, of a pair of fingers supported for swinging movements each about an axis extending heightwise of the last to spread the margin of the upper outwardly over the wipers near the end of the toe, another pair of fingers supported for movements to spread the margin of the upper outwardly at the sides of the toe in locations beyond said first-named fingers, mechanism including a member movable lengthwise of the last for imparting such outward upper-spreading movements to all said fingers, another member movable lengthwise of the last thus to operate said first-named member, means for moving said first-named member farther lengthwise of the last relatively to said other member in the course of the operation of the machine to impart further outward movements to said fingers, and additional means for thereafter retracting all said fingers bodily lengthwise of the last by continued movement of said first-named member.

19. In a lasting machine, the combination with wipers for wiping an upper around the toe end of a last into lasted position, of a pair of fingers

supported for swinging movements each about an axis extending heightwise of the last to spread the margin of the upper outwardly over the wipers near the end of the toe, another pair of fingers supported for movements to spread the margin of the upper outwardly at the sides of the toe in locations beyond said first-named fingers, mechanism including a slide movable lengthwise of the last for imparting such outward upper-spreading movements to all said fingers, another slide movable lengthwise of the last to operate said first-named slide by engagement therewith, means for moving the first-named slide farther lengthwise of the last independently of said other slide in the course of the operation of the machine to impart further outward movements to said fingers, and means arranged to be operated by continued movement of the first-named slide to retract all the fingers bodily lengthwise of the last.

20. In a lasting machine, the combination with wipers for wiping an upper around the toe end of a last into lasted position, of a plurality of upper-spreading fingers for spreading the margin of the toe end of the upper outwardly over the wipers, mechanism including a member movable lengthwise of the last to impart to said fingers outward movements widthwise of the last, and another member connected to said fingers and arranged to be operated by further movement of said first-named member to move the fingers bodily lengthwise of the last.

21. In a lasting machine, the combination with wipers for wiping an upper around the toe end of a last into lasted position, of a plurality of upper-spreading fingers for spreading the margin of the toe end of the upper outwardly over the wipers, mechanism including a slide movable lengthwise of the last to impart to said fingers outward movements widthwise of the last, and another slide arranged to be operated by further movement of said first-named slide to move the fingers bodily lengthwise of the last after the completion of their movements widthwise of the last.

22. In a lasting machine, the combination with wipers for wiping an upper around the toe end of a last into lasted position, of a plurality of upper-spreading fingers for spreading the margin of the toe end of the upper outwardly over the wipers, a carrier movable lengthwise of the last, a member for moving said fingers bodily in a direction lengthwise of the last by the movement of the carrier, and means for moving said member relatively to the carrier to impart further bodily movements in the same direction lengthwise of the last to the fingers.

23. In a lasting machine, the combination with wipers for wiping an upper around the toe end of a last into lasted position, of a plurality of upper-spreading fingers for spreading the margin of the toe end of the upper outwardly over the wipers, a carrier movable lengthwise of the last, a member initially connected to said carrier for moving the fingers bodily in a direction lengthwise of the last by the movement of the carrier, and means for disconnecting said member from the carrier and for moving it relatively to the carrier to impart further bodily movements in the same direction lengthwise of the last to the fingers.

24. In a lasting machine, the combination with wipers for wiping an upper around the toe end of a last into lasted position, of a plurality of upper-spreading fingers for spreading the margin of the toe end of the upper outwardly over the

wipers, a carrier movable lengthwise of the last, a slide supported on said carrier and initially connected thereto for moving the fingers bodily in a direction lengthwise of the last by the movement of the carrier, and means for disconnecting said slide from the carrier and for moving it relatively to the carrier to impart further bodily movements in the same direction lengthwise of the last to the fingers.

25. In a lasting machine, the combination with wipers for wiping an upper around the toe end of a last into lasted position, of a plurality of upper-spreading fingers for spreading the margin of the toe end of the upper outwardly over the wipers, mechanism including a member movable lengthwise of the last for imparting to said fingers outward upper-spreading movements widthwise of the last, a carrier movable lengthwise of the last, and a member for moving said fingers bodily lengthwise of the last by the movement of the carrier as they are moved widthwise of the last, said last-named member being arranged to be moved also relatively to the carrier by said first-named member to impart further bodily movements lengthwise of the last to the fingers.

26. In a lasting machine, the combination with wipers for wiping an upper around the toe end of a last into lasted position, of a plurality of upper-spreading fingers for spreading the margin of the toe end of the upper outwardly over the wipers, mechanism including a member movable lengthwise of the last for imparting to said fingers outward upper-spreading movements widthwise of the last, a carrier movable lengthwise of the last, a member for moving said fingers bodily lengthwise of the last by the movement of the carrier as they are moved widthwise of the last, said last-named member being arranged to be moved also relatively to the carrier by said first-named member to impart further bodily movements lengthwise of the last to the fingers, and means controlled by said first-named member for initially locking the last-named member to the carrier and for thereafter unlocking it to permit it thus to be moved relatively to the carrier.

27. In a lasting machine, the combination with wipers for wiping an upper around the toe end of a last into lasted position, of a plurality of upper-spreading fingers for spreading the margin of the toe end of the upper outwardly over the wipers, mechanism including a member movable lengthwise of the last for imparting to said fingers outward upper-spreading movements widthwise of the last, a carrier supporting said member and relatively to which the member is thus movable, said carrier being mounted for movement lengthwise of the last, and a member also supported by said carrier for moving the fingers bodily lengthwise of the last by the movement of the carrier as they are moved widthwise of the last, said

last-named member being arranged to be moved also relatively to the carrier by said first-named member to impart further bodily movements lengthwise of the last to the fingers.

5 28. In a lasting machine, the combination with wipers for wiping an upper around the toe end of a last into lasted position, of a plurality of upper-spreading fingers for spreading the margin of the toe end of the upper outwardly over the wipers, mechanism including a slide movable lengthwise of the last for imparting to said fingers outward upper-spreading movements widthwise of the last, a carrier supporting said slide and relatively to which the slide is thus movable, said carrier being mounted for movement lengthwise of the last, and another slide also supported by said carrier and initially connected thereto for moving the fingers bodily lengthwise of the last by the movement of the carrier as they are moved widthwise of the last, said other slide being arranged to be moved also relatively to the carrier by said first-named slide to impart further bodily movements lengthwise of the last to the fingers.

29. In a lasting machine, a pair of auxiliary 25 wiping devices arranged to rest on toe-embracing wipers in the machine and to be moved heightwise of a last in wiping engagement with an upper at the sides of the toe by said wipers, each of said auxiliary wiping devices comprising a pair of 30 wiper plates located one beyond the other lengthwise of the edge of the shoe bottom and each mounted for movement independently of the other about a separate axis extending heightwise of the last to permit them to adjust themselves to the contour of the toe.

35 30. In a lasting machine, a pair of auxiliary wiping devices arranged to rest on toe-embracing wipers in the machine and to be moved heightwise of a last in wiping engagement with an upper at the sides of the toe by said wipers, each 40 of said auxiliary wiping devices including a pair of wiper plates located one beyond the other lengthwise of the edge of the shoe bottom and each freely movable independently of the other 45 about a separate axis extending heightwise of the last and further including a support for said pair of plates freely movable about another such axis to permit the plates to adjust themselves to the contour of the toe.

50 STANLEY ERNEST FRAMPTON.
